Patented Aug. 27, 1918.

Inventor:
Alfred E. Holmes.
By Cheever & Cox *Attys.*

UNITED STATES PATENT OFFICE.

ALFRED E. HOLMES, OF CHICAGO, ILLINOIS.

WRENCH.

1,276,918.

Specification of Letters Patent. Patented Aug. 27, 1918.

Application filed June 21, 1917. Serial No. 175,984.

To all whom it may concern:

Be it known that I, ALFRED E. HOLMES, a citizen of the United States, residing at Chicago, in the county of Cook and State of Illinois, have invented a certain new and useful Improvement in Wrenches, of which the following is a specification.

My invention relates to wrenches of the type sometimes known as "pipe wrenches".
10 My present wrench is analogous in some respects to the one shown in Patent No. 1,117,574, granted to me November 17, 1914. In certain aspects my present wrench is an improvement over the one shown in said patent. The object of the present invention is to provide a wrench in which the movable jaw is controlled by a worm wheel instead of a ratchet, the worm wheel being at all times in mesh with the movable jaw and 20 permitting finer adjustment than is obtainable with a ratchet. Viewed in another way, it is an object of my present invention to provide a wrench in which the movable jaw is operated by a worm, the diameter of 25 which is not appreciably greater than the thickness of the wrench. This makes it possible to insert the wrench in spaces which a thicker wrench could not enter. It also prevents the worm from readily coming into 30 contact with external objects, and thus having its adjustment changed or causing damage to such external object. Other characteristics of the invention will become apparent as the description proceeds.

35 I accomplish my objects by the construction shown in the accompanying drawing in which:

Figure 1 is a perspective view of the complete wrench.

40 Fig. 2 is a side view thereof showing the near half of the saddle cut away.

Fig. 3 is a transverse section on the line 3—3, Fig. 2.

Fig. 4 is similar to Fig. 2, but shows the 45 movable jaw in non-acting position.

Similar numerals refer to similar parts throughout the several views.

The handle 1 carries a fixed jaw 2 which is provided with teeth 3 at the outer end 50 for gripping the work. A saddle 4 is fastened to the fixed jaw, this being an arched piece which extends over the back of the movable jaw 5. This movable jaw has gripping teeth 6 which coöperate with the teeth 3 to grip the work. The front or inner side of the movable jaw is provided with teeth 55

7 in the form of a rack which engages and is operated by the worm 8. The edges of the worm are knurled to facilitate manipulation, and the saddle has openings 4^a in the 60 sides to afford access to the worm. Thus the saddle virtually forms a housing for the worm and the other operating parts of the tool. Said worm is rotatably mounted upon a shaft 9 which is pivoted at its outer end 65 upon the pin 10 carried by the saddle 4. A head 11 is formed at the outer end of the shaft and this has a cylindrical surface 12 which bears against a corresponding surface 13 formed on the fixed jaw, as best shown 70 in Figs. 2 and 4. These cylindrical surfaces are concentric with the pin 10 and relieve the pin of all of the strain when the tool is in action. A spacing collar 14 holds the worm in position on the shaft and this collar is held in position by swaging an annular shoulder 15 on the inner end of the shaft. The diameter of the edges of the worm is little, if any, greater than the width of the saddle. Thus the worm is largely if 80 not entirely protected by the saddle. It will be understood, of course, that these structural details may be altered if desired, the most important characteristic being that the worm 8 is rotatable upon shaft 9 and said 85 shaft is pivotally mounted upon the fixed jaw in such manner as to swing through a limited arc in the plane of the tool.

A spring 17 is fastened to the back of the handle 1 and, at its free end, has a seat 18 90 in which sleeve 14 rests. The spring tends to hold the worm in engagement with the rack teeth 7 for all positions of the movable jaw. While not essential, this construction reduces friction between the non-rotating 95 spring and the rotating worm, for it will be seen that the spring bears against the collar and the worm is rotatable independently of the collar. A stop 20 rises from the back of the fixed jaw in position to engage the 100 collar 14 and prevent the worm from descending far enough to actually make contact with the jaw. By thus contacting the collar instead of the worm, friction, when the worm rotates, is further reduced.

105 In operation, when the wrench is applied to the pipe, rod, or other piece of work, the operator increases the jaw opening by depressing the inner end of the movable jaw and bringing it to the position shown in 110 Fig. 4. The tool is then applied to the work and the movable jaw released, whereupon

the spring 17 causes it to move toward the position shown in Fig. 2. The operator may adjust the movable jaw relatively to the fixed jaw by rotating the worm either before or after the tool is applied to the work. When the tool is in use it will exert a very strong gripping action upon the work, the gripping action increasing with the degree of pressure applied upon the tool handle in the manner understood by those familiar with this general type of tool.

As a result of this entire construction, the wrench may be manipulated very readily, and very fine adjustments may be obtained by rotating the worm. As the edges of the worm project little, if any, beyond the sides of the saddle, there is no danger that contact with surrounding objects will disturb the adjustment of the tool either while it is in use or at any other time. It also enables the tool to enter and be used in spaces which would otherwise be too small. The parts are simple in form and possess great strength in spite of the fact that they occupy less space than other tools of this general kind.

Having thus described my invention, what I claim as new and desire to secure by Letters Patent, is:

1. A wrench comprising a fixed jaw having a shank, a saddle fastened to the shank, and arching the back thereof, a movable jaw having a shank extending through the saddle for both longitudinal movement and movement toward and away from the shank of the fixed jaw, a rack on the face of the

shank of the movable jaw adjacent the shank of the fixed jaw, a shaft pivoted between the shanks of the fixed and movable jaws, and having a shoulder on the free end thereof, a worm rotatable on said shaft and coöperating with said rack; a spacing collar loose on said shaft between the worm and shoulder, a stop on the shank of the fixed jaw engageable with said collar to limit movement of the worm in one direction to a position of non-engagement with the shank of the fixed jaw, and spring means constantly urging the worm toward the shank of the movable jaw. 40 45

2. A wrench comprising a fixed jaw having a shank, a saddle fastened to the shank and arching the back thereof, a movable jaw having a shank extending through the saddle for both longitudinal movement and movement toward and away from the shank of the fixed jaw, a rack on the face of the shank of the movable jaw adjacent the shank of the fixed jaw, a shaft pivoted between the shanks of the fixed and movable jaws, a worm rotatable on said shaft and coöperating with said rack, and a leaf spring secured to the shank of the fixed jaw and having its free end curved transversely to slidably embrace the shaft and permit unrestricted rotation of the latter, said spring constantly urging the worm toward the shank of the movable jaw. 50 55 60 65

In witness whereof I have hereunto subscribed my name.

ALFRED E. HOLMES.
